DESIGN FOR A DEFECATOR

William C. Groeniger, Columbus, Ohio

Application October 3, 1938, Serial No. 80,214

Term of patent 14 years

To all whom it may concern:

Be it known that I, William C. Groeniger, a citizen of the United States of America, residing at Columbus, county of Franklin, State of Ohio, have invented a new, original, and ornamental Design for a Defecator, of which the following is a specification, reference being had to the accompanying drawing, forming part thereof.

In the drawing:

Fig. 1 is a perspective of a defecator embodying my design;

Fig. 2 is a top plan view of the same;

Fig. 3 is a side elevation of the same; and

Fig. 4 is a front elevation of the same.

I claim:

The ornamental design for a defecator, substantially as shown.

WILLIAM C. GROENIGER.
